DEVICE FOR OPERATING MOLD MEMBERS

Application filed September 4, 1928. Serial No. 303,781.

The invention relates to mold operating mechanisms and refers more particularly to devices for operating mold cores. One of the objects of the invention is to provide a simple 5 construction of operating device which will readily move a mold member to or from its casting or operative position. Another object is to provide a cam for operating the mold member, which cam is bodily movable 10 relative to the base of the mold. Further objects of the invention reside in the novel features of construction and combinations and arrangements of parts as more fully hereinafter set forth.

15 In the drawings:—

Figure 1 is a sectional elevation of the mold and an operating device embodying our invention;

Figure 2 is a cross section on the line 2—2 20 of Figure 1;

Figure 3 is a bottom plan view thereof.

As shown in the present instance, the mold 1 has the hinged permanent mold sections 2 and 3, which are mounted upon the metal 25 base 4. The legs 5 secured to the base at its corners support the base. 7 is a movable permanent mold member or core which slidably engages the base and is adapted to extend upwardly therethrough.

30 For raising this core into castings or operative position and lowering the core, we have provided the rotatable cam 8 which is bodily movable relative to the base and which has the plate 9 and the diametrically opposite 35 pairs of upper and lower cam portions 10 and 11 respectively. These cam portions are located at the periphery of the plate and extend from its upper and lower sides. They are also longitudinally arcuate and have substantially parallel bearing faces which are inclined relative to the plate. 12 are diametrically opposite brackets secured to and depending from the base 4 and having grooves 40 13 in their inner faces for receiving the cam

45 portions, the upper end lower faces of these grooves having the same inclination as the bearing faces of the cam portions. The inclination is within the angle of friction so that the cam will automatically remain in its positions of rotative adjustment. The core has

the reduced portion 14 extending axially downwardly through the plate 9 of the cam, there being preferably a slight clearance between this reduced portion and the plate. The core also has the downwardly facing annular shoulder 15 engageable with the upper face of the plate and further has secured to the lower end of its reduced portion the collar 16 forming the annular shoulder 17 for engaging the lower face of the plate. Both the 55 shoulders 15 and 17 are preferably convex and are spaced apart a distance slightly greater than the thickness of the plate so that rotation of the cam will not cause the core to bind in the base. 60

65 For angularly locating the core so that it will assume its correct casting or operative position, there is the key 18, which extends longitudinally of and is secured to the portion of the core slidably engaging the base 70 4, this key slidably engaging in the groove 19 formed in the base. 20 is a handle secured to the plate 9 of the cam and extending horizontally toward the front of the apparatus, the brackets 12 being at the sides so 75 that they will not interfere with the angular movement of the handle in rotating the cam. The front legs 5 are so positioned that they will contact with this handle to limit its angular movement, the arrangement being such 80 that when the handle is in contact with one of these legs the core is in its casting or operative position and when the handle is in contact with the other of these legs the core is in its lowermost position. 85

What we claim as our invention is:

1. The combination with a base and a mold member movable relative thereto, of a rotatable cam having a plate and cam portions on opposite sides of said plate with substantially parallel bearing faces, means fixed to said base for engaging said bearing faces, and means for securing said mold member to said cam. 90

2. The combination with a base and a longitudinally movable mold member extending transversely of said base, of a rotatable cam having a plate and cam portions on opposite sides of said plate with substantially parallel bearing faces, means secured to said 100

base for engaging said bearing faces, means for securing said mold member to said cam, and means for holding said mold member from rotation.

- 5 3. The combination with a base and a mold member extending through said base and movable transversely thereof, of a rotatable cam having a plate and pairs of arcuate cam portions on said plate, each pair having substantially parallel faces on opposite sides of said plate and inclined relative thereto, means for securing said mold member to said plate, and brackets secured to said base and provided with grooves for receiving said pairs of cam portions.
- 10 4. The combination with a base and a mold member movable transversely of said base, of a rotatable cam below said base having a plate and diametrically opposite pairs of arcuate cam portions, each pair having substantially parallel bearing faces on opposite sides of said plate and inclined relative thereto, said plate having an opening therethrough concentric with said cam portions and said mold member having a portion extending through said opening, shoulder forming means upon said mold member engaging opposite sides of said plate, and diametrically opposite brackets secured to and depending from said base and having grooves for receiving pairs of arcuate cam portions.
- 15 5. The combination with a base and a mold member movable relative thereto, of a movable cam comprising a plate having cam portions with substantially parallel bearing faces, means for operatively connecting said mold member to said cam, and fixed means engaging and cooperating with said bearing faces for imparting movement to said mold member upon movement of said cam.
- 20 6. The combination with a base and a mold member movable relatively thereto, of a rotatable cam comprising a plate having a cam portion, means for operatively connecting said mold member to said cam, and fixed means engaging and cooperating with said cam portion for imparting movement to said mold member upon rotation of said cam.
- 25 7. The combination with a base and a mold member movable relative thereto, of a movable cam operatively connected to said mold member and having a cam portion, and fixed means for engaging and cooperating with said cam portion for imparting movement to said mold member upon movement of said cam.
